1

This invention relates to oscillation generators of the type having a cathode ray tube wherein the frequency of the oscillations generated is a function of the cyclic rate of deflection of the electron beam; the frequency being also dependent upon the rate at which the electron beam is caused to sweep across a succession of target anode surfaces and to penetrate a plurality of apertures between said surfaces. Although, in perfecting our invention, we have adopted certain well known features of cathode ray tube generators, we have, nevertheless, contributed materially to the useful scope of such devices by providing a novel construction of cavity resonator within the envelope of the cathode ray tube.

In our system a current impulse is produced in an output circuit connected to the receiving electrode in each instance when the receiving electrode is struck by the beam, the frequency of said impulses being determined by the product of the frequency of the controlling oscillation and the number of apertures over which the beam is passed during one cycle of the controlling oscillation. The output circuit is made to oscillate by the current impulses and is tuned to the frequency of the current impulses. To obtain a high power output oscillation the output circuit should present a high impedance to this frequency.

In devices of the said kind hitherto known for generating oscillations having a wave length of several decimeters difficulties were experienced in the construction of an output circuit presenting a sufficient impedance to the oscillations to be generated.

According to the invention these difficulties are obviated by making use of a device in which two of the apertured electrodes or one of these electrodes and the receiving electrode are united to form a hollow member which constitutes a resonant circuit tuned to the frequency of the oscillations to be generated.

The invention will be more fully explained by reference to the accompanying drawing forming a part of the specification and in which:

Fig. 1 is a diagram partially in section and partially schematic illustrating a device according to the invention.

Fig. 2 is a plan view of a component part of the device illustrated in Fig. 1.

Fig. 3 is a diagram of another device according to the invention.

Fig. 4 is a diagram illustrating a further embodiment of the invention.

Fig. 5 is a plan view of an alternate component

2

part of the devices illustrated in the foregoing figures and

Fig. 6 is a diagram illustrating still another device according to the invention.

The device shown in Fig. 1 comprises a cathode ray tube furnished with the usual means for generating a beam of electrons, the same means consisting of a cathode 1, a control electrode 3 and an accelerating electrode 5. The tube is represented in axial section. To concentrate the beam there may be provided a focussing coil 7 energized by direct current together with a magnetic screen 8 by which the deflecting means of the tube are withdrawn from the influence of the field of coil 7. The deflecting means of the tube consist of a set of deflecting plates 9 which are connected to the end of a resonant circuit which is represented in Fig. 1 by a capacity 11 and an inductance coil 13 which coil is coupled to a coupling coil 15. At the other end of the tube there are provided, coaxially with the device described hereinbefore, an apertured electrode 17 and a receiving electrode 19 which, as will be explained more in detail hereinafter, are united according to the invention to form a hollow member 21 by means of an annular metal box 23, which member is completely closed except for an annular aperture 25 in the electrode 17. Within the hollow member 21 a grid 27 which extends normally to the axis is located about mid-way between the electrodes 17 and 19. This grid is connected for high frequencies through a condenser 30 to the box 23 and is earthed for high frequencies across a condenser 29. The electrode 19 is connected to the outer conductor 31, the electrode 17 being connected to the interior conductor 33 of a concentric transmission line 31, 33 which at the other end is connected to a load circuit, for instance, an antenna 35. From a source of direct current, for instance, a battery 41, suitable positive voltages relatively to the cathode 1 are supplied to the electrode 5 and the member 21, the electrode 3 receiving a negative voltage through a secondary winding 45 of a transformer 43, 45.

The device 1, 3, 5 produces a beam of electrons, indicated by a dotted line 2, which beam can be concentrated by the focussing coil 7. To the oscillatory circuit 11, 13 connected to the deflecting plates 9 a high frequency controlling voltage is supplied through the coupling coil 15 whereby the beam is caused to travel to and fro, the point at which the beam hits the electrode 17 travelling over this electrode between two extreme points 55 P and Q. As appears from Fig. 2, which is a front

view of the member 21, four times a group of electrons of the beam falls through the annular aperture 25 on the electrode 19, per to and fro motion of the beam that is, per cycle of the controlling oscillation supplied to the electrodes 9. 6 During the travel of such a group of electrons from the electrode 17 to the electrode 19 a current impulse is produced in an external circuit which may be connected between the said electrodes, the current passing from the electrode 17 10 to the electrode 19. The electrodes 17 and 19 are combined to form a hollow shell 21 which constitutes a resonant circuit tuned to the frequency of the oscillation to be generated. In this case 15 the capacity between the electrodes 17 and 19 constitutes the tuning capacity, the tuning inductance being mainly constituted by the electrodes 17 and 19. The resonant circuit thus constituted serves as an external circuit between the electrodes 17 and 19 and is made to oscillate by the current impulses occurring between these electrodes; the frequency of the generated oscillation is the same as that of the current impulses, in the case referred to, consequently the 20 four-fold frequency of the controlling oscillation.

When making use of the step to be taken according to the invention a resonant circuit is formed which is connected between the electrodes 17 and 19 and which even at very high frequencies exhibits very small losses, and hence a high impedance as a result of which a considerable output energy is obtainable. The high degree of freedom of loss of the circuit 17, 19, 23 is a result of the very small losses in the inductance constituted by the connection between the electrodes 17 and 19. This connection is constituted by a single turn having a large surface owing to which the loss resistance for high frequency currents is small. Moreover, the magnetic flux is closed in itself and extends entirely within the member 21. Leakage fields liable to strike metal parts and causing losses are thus avoided. Moreover, connecting lines are superfluous, since the electrodes 17 and 19 form themselves part of the resonant circuit.

From experiments and also upon calculation it appears that for suitable operation the distance between electrodes 17 and 19, taking into account the velocity of the electrons, must be so chosen that the transit time of an electron between the electrodes 17 and 19 is less than half a cycle of the output oscillation. This means that the distance between electrodes 17 and 19 will generally be very small. To ensure that the connection through which these electrodes are united to form a hollow member has a considerable inductance, the connection is preferably constituted by an annular metal box 23 which extends coaxially with the electrode 17 and 19 and whose diameter and axial length is larger than the diameter and distance between the electrodes 17 and 19 respectively.

The ends of the resonant circuit constituted by the hollow member 21 are located in the center of the electrodes 17 and 19 respectively. The oscillatory energy available in the circuit may be supplied to a load circuit, for instance, to the antenna 35, through the intermediary of the transmission line 31, 33 whose two conductors are connected respectively to the said centers.

The transit time of the electrons between the electrodes 17 and 19 is determined by their average velocity and by the distance between these electrodes. The electrons enter the member 21 at a definite initial speed and are slowed down therein due to the fact that they cede energy.

After having traversed the member 21 in an axial direction the electrons hit the electrode 19, it being possible that secondary electrons are dislodged which travel to the electrode 17. By these electrons a current impulse from the electrode 19 to the electrode 17 is produced in the output circuit, which impulse is opposite to that producing the output oscillation and consequently counteracts the latter. Therefore, according to the invention, the receiving electrode 19 preferably has no or only a small secondary emission, since it is coated, for instance, with a layer of soot at least on the side where the electrons are received.

In order to prevent secondary electrons dislodged from the electrode 19 from reaching the electrode 17, according to the invention, the grid 27, which is preferably earthed for high frequencies across a condenser 29, is located about mid-way between the electrodes 17 and 19 and parallel therewith, which grid repels any secondary electrons issuing from the electrode 19. The grid 27 is connected for high frequencies through the condenser 30 to the middle of the mantle of the box 23. The center of the resonant circuit constituted by the member 21 is consequently earthed for high frequencies across condensers 29 and 30.

The grid 27 also has another function. During one-half of the cycle of the output oscillation the electrode 19 is negative with respect to the electrode 17. In the absence of a grid 27 a group of electrons staying in front of the aperture 25 during this half cycle is attracted by the electrode 17 and repelled by the electrode 19 so that the electrons are likely to be scattered and instead of passing through the aperture 25 to the electrode 19 travel to the electrode 17. By providing the grid 27 the risk thereof is greatly reduced, because during the said half cycle the negative voltage of the grid 27 with respect to the electrode 17 is only half that of the electrode 19, since the grid 27 is connected for high frequencies to a mid-tap of the circuit 17, 19, 23.

Instead of an annular aperture the electrode 17 may exhibit two slit-shaped apertures 25 through which the beam of electrons passes alternately. According to the invention, however, an annular aperture is preferably used. In fact, the line PQ along which travels the point where the beam hits the electrode 17 tends to turn about the axis of the cathode ray tube and to occupy, for instance, the position P'Q'. As a result of the annular shape of the aperture 25 the distance between the points where the beam passes through the electrode 17 is always the same, it being thus ensured that the current impulses relatively to one another always occur at the correct moments as long as the deflection of the beam of electrons under the action of the controlling voltage, that is, the length of line PQ, remains the same.

The device represented in Fig. 1 is also adapted for generating modulated oscillations. For this purpose a modulating voltage is supplied to the primary winding 43 of transformer 43, 45. The modulating voltage induced in the secondary winding 45 of this transformer is supplied to the control electrode 3 and causes intensity variations of the beam of electrons, which correspond to the modulating voltage and as a result of which the maximum amplitude of the output oscillation is varied proportionally to the momentary amplitude of the modulating voltage.

Fig. 3 represents partly in section, and partly

in perspective another form of construction of the device according to the invention. This form of construction substantially corresponds to that shown in Fig. 1 but it comprises a device for generating a web-shaped beam of electrons, by means of which a large intensity of the beam of electrons is obtained. The cathode 4 is elongated and the control electrode 3 exhibits a slit-shaped aperture through which emerges the web-shaped beam 2. Acceleration and concentration of the beam is effected by the electrodes 9 which serve as deflecting plates at the same time; to this end they are connected, in the manner shown already in Fig. 1; to a resonant circuit 11, 13 and via the center of coil 13 a positive auxiliary voltage is supplied from the battery 41 to the two plates. The operation corresponds to that of the device shown in Fig. 1.

Figs. 4 and 5 represent another form of construction of the device according to the invention, by means of which an output oscillation can be obtained whose frequency amounts to many times that of the controlling oscillation. Fig. 4 largely corresponds to Fig. 1. However, the device shown in Fig. 4 comprises another set of deflecting plates 10 which extend normally to the plates 9. The plates 10 are connected to a resonant circuit represented by a condenser 12 and a coil 14. The coil 14 is coupled to a coupling coil 16 to which, as well as to coil 15, the controlling oscillation is supplied. The circuits 11, 13 and 12, 14 are slightly detuned relatively to one another so that the alternating voltages occurring across the circuits differ in phase by 90°. Thus a rotary electric field is set up between the deflecting plates 9 and 10 as a result of which the beam acquires a rotary movement about its original direction as an axis. Owing to this movement the beam is made to follow a circular path over the electrode 17 which electrode in the present form of construction of the device, according to the invention, is shaped as shown in Fig. 5, viewed in the direction of travel of the electrons. The electrode 17 exhibits a number of apertures 26 located along the periphery of a circle. The amplitudes of the alternating voltage occurring between the deflecting plates 9 and 10 respectively are adjusted so that the beam passes over the apertures 26 and alternately hits the electrode 17 and, through one of the apertures 26, the electrode 19, the current impulses produced in the manner set out above exciting the resonant circuit constituted by the hollow member 21. The beam performs one revolution per cycle of the controlling oscillation, the number of current impulses produced corresponding to the number of apertures 26. Consequently, the number of current impulses per second, i. e., the frequency of the output oscillation corresponds to the frequency of the controlling oscillation multiplied by the number of apertures 26. At variance with Fig. 1 the output energy in the device shown in Fig. 4 is taken from the resonant circuit 17, 23, 19 by means of a loop 37 which is led in an insulated manner through the wall of box 23, this loop being coupled to the magnetic flux of the circuit and connected to two output terminals 39 outside of the member 21. However, use may also be made of the device bearing the reference numbers 31, 33, 35 in Fig. 1.

Fig. 6 represents one embodiment of the invention which substantially corresponds to that shown in Fig. 4, but which comprises more than one apertured electrode in such manner that cor-

responding apertures of the succeeding electrodes in the direction of the beam of electrons are in line with one another. According to the invention there are provided three apertured electrodes 17, 18 and 19. In the present form of construction two neighboring electrodes 17 and 19 located nearest the receiving electrode 20 are united to form a hollow member 51 by means of a preferably annular metal box 23 which is earthed for high frequencies through a condenser 52, the electrodes 18 and 20 being earthed for the frequency of the output oscillation by means of condensers 53 and 55 respectively. The D. C. voltage supplied to the hollow member 51 amounts to several times the voltage supplied to the electrodes 18 and 20; the said voltages may amount, for instance, to 5000 volts and 500 volts respectively.

The electrons from the beam 2 are alternately intercepted by the electrodes 18 and 20. Since these electrodes have a comparatively low D. C. voltage and no alternating voltage, little energy is lost so that a satisfactory efficiency can be obtained. The electrodes 17 and 19 are not hit by electrons, so that there does not flow direct current to these electrodes.

As has already been set out, the distance between the electrodes 17 and 19 is preferably chosen so that the transit time of the electrons between the said electrodes amounts at most to half a cycle of the output oscillation. The distance between the electrodes 18 and 17 and between the electrodes 19 and 20 may be much larger; the distance between the electrodes 19 and 20 is preferably chosen so that a space charge accumulates between them, which results in that any secondary electrons dislodged from the electrode 20 return to this electrode.

We claim:

1. An electronic device comprising an evacuated envelope containing an electron gun for emitting a focused electron beam, deflecting means along the trajectory of said gun for periodically deflecting said beam, a metallic shell constituting a cavity resonator and having two opposed walls which are spaced apart in accordance with a functional requirement concerning the transit time of electrons passable therebetween, a suppressor grid electrode substantially midway between and lying in a plane parallel to said opposed walls of said cavity resonator, said shell having a peripheral wall constituting a metallic connection between said two opposed walls, one of said opposed walls having apertures in registry with said trajectory for the intermittent entry into said cavity resonator of electrons emitted by said gun, and an output circuit comprising two conductors individually connected to each of said opposed walls.

2. An electronic device comprising an evacuated envelope containing an electron gun for emitting a focused electron beam, deflecting means along the trajectory of said gun for periodically deflecting said beam, a metallic shell constituting a cavity resonator and having two opposed disc wall portions which are spaced apart in accordance with a functional requirement concerning the transit time of electrons passable therebetween and two opposed annular wall portions exterior to the circumference of said disc wall portions, said annular wall portions being spaced farther apart than said disc wall portions and having a peripheral wall constituting a metallic connection between said two opposed annular wall portions, one of said opposed disc

wall portions having apertures in registry with said trajectory for the intermittent entry into said cavity resonator of electrons emitted by said gun, and an output circuit comprising two conductors individually connected to each of said two opposed disc wall portions.

3. An electronic device comprising an evacuated envelope containing an electron gun for emitting a focused electron beam, deflecting means along the trajectory of said gun for periodically deflecting said beam, a metallic shell constituting a cavity resonator and having two opposed walls which are spaced apart in accordance with a functional requirement concerning the transit time of electrons passable therebetween, said shell having a peripheral wall constituting a metallic connection between said two opposed walls, an electrode having apertures interposed between said electron gun and said metallic shell, each of said opposed walls having apertures, the apertures of said electrode and said walls being in registry with said trajectory thereby permitting said electron beam to penetrate corresponding apertures in a straight path, and an output circuit comprising two conductors individually connected to each of said two opposed walls.

4. An oscillation generator comprising a cavity resonator having an apertured conductive shell, an output coupling connected to said shell, electrode plates external to said shell and disposed in capacitively reactive relation thereto, one of said plates having apertures in alignment with those of said shell, and excitation means for said resonator comprising an electron beam projector having a trajectory registry with said apertures, and beam deflecting means disposed along said trajectory for directing a flow of electrons through the apertures of said plate and of said shell.

5. A cathode ray tube having an electron gun for emitting an electron beam, a cavity resonator having both inner and outer electrode surfaces disposed in the path of the electron beam, said electrode surfaces including two opposed flat portions both normal to the axis of said beam, but

one only of which is apertured, namely, the portion which faces said gun, deflecting means disposed along the trajectory of said gun for periodically deflecting electrons of said beam as they travel toward said cavity resonator, said resonator constituting means for causing oscillations to be generated at a frequency which is high relative to the oscillatory rate of deflection of said electron beam.

10 6. A cathode ray tube in accordance with claim 5 and including a suppressor grid mounted within said cavity resonator.

15 7. An ultra high frequency generator comprising a cathode ray tube having an electron gun and beam deflecting means disposed along the trajectory of said gun, a cavity resonator comprising a system of target electrodes, one of which, facing the gun, has apertures, a substantially toroidal envelope interconnecting said target electrodes, and means including a suppressor grid electrode situated within said cavity resonator for controlling the flow of secondary electrons between one and the other of said target electrodes.
